UNITED STATES PATENT OFFICE.

JAMES LUKER, OF NEW YORK, N. Y.

CASE FOR HATS.

SPECIFICATION forming part of Letters Patent No. 293,183, dated February 5, 1884.

Application filed April 18, 1883. (No model.)

To all whom it may concern:

Be it known that I, JAMES LUKER, of New York, in the county and State of New York, have invented a certain new and useful Improvement in Cases for Hats, of which the following is a specification.

The object of this improvement is to produce a case in which a hat such as is worn by a Knight Templar may be conveniently and safely carried from place to place.

The improvement consists in the combination, in a hat-case, of a body portion having an upper compartment shaped internally to approximate to the external contour of a hat such as is worn by a Knight Templar, and adapted to accommodate the hat in an upright position; a handle at the top of the body portion, which will be adjacent to the top of the hat; a strap or straps adapted to extend across the body portion under the hat, so as to support the hat and retain it in its compartment; a lower compartment into which the feather of the hat may extend, and in which other articles may be placed; and a cover applied to the bottom of the body portion, and forming the bottom of said lower compartment.

In the accompanying drawings, Figure 1 is a longitudinal section of a case embodying my improvement, and Fig. 2 is a transverse section of the same.

Similar letters of reference designate corresponding parts in both figures.

A designates the body of the case, and B designates the cover thereof. The body of the case has sides, which are curved outwardly or convexly at the middle portion, *a*, of the top, and in reverse directions toward the ends, and below these curved portions are straight portions C. Between the sides extends a strip of material which forms the top and ends of the body of the case. The body of the case is preferably made wider at the middle than at the ends. It will be seen that the upper portion of the interior of the body of the case approximates to the external contour of a hat of the kind worn by a Knight Templar, and is adapted to accommodate the hat in an upright position.

C designates straps extending across the lower part of the body of the case, and divid-

ing it into two compartments. The upper compartment, which consists of the part of the body that conforms to the hat, receives the hat, and the lower compartment, which consists of the portion of the body that is between the straight portions *c*, receives the end of the feather, and serves, also, to accommodate the regalia and gloves of a Knight Templar. The straps C are attached to opposite portions of the sides of the body of the case, and are shown as made in sections, whose ends are united by buckles or fasteners *d*. The end of these sections, when thus united, may be unfastened and refastened at will, to facilitate the insertion and removal of the hat. These straps can be made of india-rubber, cloth, or other suitable material, and they support the hat and retain it in place in its compartment. The cover B of the case has a rim, which fits around the lower portion of the body of the case. It is secured in place by straps D, which are fastened at one end to the body of the case, extend thence across the cover, and at the other ends are fastened to short straps D' by means of buckles *e*. By unfastening these straps the cover may be removed at pleasure.

It will be observed that a hat placed in this case will be supported upon the straps C, and that the regalia and gloves will be supported upon the cover, and hence will not by their weight crush the feather of the hat or entail any injury to the hat. The articles to be kept in the case will preferably be placed in the body of the case, while the latter is in an inverted position.

The upper portion of the body of the case is provided with a handle, E, whereby the case may be easily carried.

This case may be made of various materials. It will be advantageous to make it of sheet metal in some cases. I prefer, however, to make it of pasteboard covered with leather.

The straps C D D' may be secured to the body of the case in any suitable manner. I have shown rivets *f*, which pass through the sides of the body of the case and through the straps C D D'.

This case will not only keep a hat in good condition, but will be light, neat, and convenient to carry.

What I claim as my invention, and desire to secure by Letters Patent, is—

In a hat-case, the combination of a body portion having an upper compartment shaped internally to approximate to the external contour of a hat such as is worn by a Knight Templar, and adapted to contain the hat in an upright position, a handle at the top of the body portion, which will be adjacent to the top of the hat, a strap or straps adapted to extend across the body portion under the hat, so as to

support the hat and retain it in its compartment, a lower compartment into which the feather of the hat may extend, and in which other articles may be placed, and a cover applied to the bottom of the body portion, and forming the bottom of said lower compartment, substantially as specified. 15

Correction in Letters Patent No. 293,183.

It is hereby certified that in Letters Patent No. 293,183, granted February 5, 1884, upon the application of James Luker, of New York, New York, for an improvement in "Cases for Hats," an error appears in the printed specification requiring correction as follows: In line 39, page 1, the reference letter "C" should read *e*; and that the patent should be read with this correction therein to make it conform to the record of the case in the Patent Office.

Signed, countersigned, and sealed this 19th day of February, A. D. 1884.

[SEAL.]

M. L. JOSLYN,
Acting Secretary of the Interior.
